UNITED STATES PATENT OFFICE.

LYMAN R. ROBERTS, OF RUTHERFORD, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,230,517.

Specification of Letters Patent. Patented June 19, 1917.

Application filed September 30, 1913. Serial No. 792,539.

To all whom it may concern:

Be it known that I, LYMAN R. ROBERTS, a citizen of the United States, residing in Rutherford, in the county of Bergen and 5 State of New Jersey, have invented certain new and useful Improvements in Type-Writing Machines, of which the following is a specification.

My invention relates to typewriting machines and particularly to an improved form 10 and arrangement of mechanism for shifting the platen.

The platen frame may be pivoted on the carriage and is shiftable to upper and lower 15 case positions by means of a tilting frame mounted on the carriage and comprising arms or levers to engage and lift the platen frame, and a depressible guide rail mounted on said arms in rear of the carriage, a non- 20 traveling shifter in engagement with said rail being movable downwardly by means of a shift key or keys. A simple and practical form of platen-shifting mechanism is thereby obtained and the parts are conveniently 25 disposed so as not to encroach on space required for other mechanism.

The shifter may be in the form of a roller running on said rail, and the roller may be mounted in a head adjustably connected to a 30 vertical link guided through a bracket on the machine frame, an adjustable stop on the link engaging said bracket to limit the downward movement; said link connected at its lower end to a rock arm fixed to a 35 rock shaft carrying additional rock arms actuated by shift key levers.

Other features and advantages will hereinafter appear.

In the accompanying drawings, 40 Figure 1 is a perspective rear view of a typewriting machine embodying my invention, the machine frame being partly broken away, and various portions of the mechanism, which form no part of the present invention, being omitted.

Fig. 2 is an end elevational view looking 45 from the left-hand end of the machine.

Fig. 3 is a similar view, but with portions omitted and showing the position of parts 50 when the shift key is depressed.

The carriage 1 is mounted in a machine frame 2, being supported and guided between guide rails 3, which, together with the carriage, form raceways for antifriction 55 rollers 4. A rotary platen 5, secured to an

axle 6 to which are attached hand wheels 7, is mounted on a platen frame comprising end plates 8 and 9, in which the platen axle is journaled, said plates being connected by tie-rods 10 and 11. The ends of the rod 10 60 to extend beyond the end plates 8 and 9 to form pivots seated in recesses 12 in end brackets 13 forming part of the carriage 1. The platen frame is shiftable about the axis of the rod 10 as a center, to upper and lower 65 case positions, the platen axle 6 being guided in arc-shaped slots 14 in the brackets 13, said axle 6 being seated in the bottom of said slots when the platen is in lower-case position. Type-bars 15 carrying upper and 70 lower case types 16 and 17, are adapted to be swung about their pivots 18 by the usual key-operated mechanism, to bring the types against the front face of the platen.

The platen is shifted by means of a rock 75 frame, comprising horizontally-disposed end arms or levers 19, pivoted at 20 to lugs 21 on the carriage, said arms connected at their rear ends by a tie-rod 22 located at the rear of the carriage and extending in the direction of the carriage travel. The forward ends of the arms 19 extend beneath the tie-rod 11, so that when the rod 22 is pulled 80 downwardly to tilt the frame 19, 22, the platen frame is shifted upwardly to bring the platen to upper-case position.

The platen-shifting frame is adapted to be actuated by shift keys 23 on the forward ends of key levers 24 pivoted on a rod 25 fixed at its ends in the machine frame 2. 90 The rear ends of the key levers carry anti-friction rollers 26, bearing against cam surfaces 27 formed on rock arms 28 fixed to a rock shaft 29 journaled in the machine frame.

Also fixed to the shaft 29, preferably about midway between the ends of the machine, is a rock arm 30 extending rearwardly and at its free end connected to a vertically-disposed link 31, the upper end of which is 100 threaded into a head 32 carrying a roller 33, which, during the travel of the carriage, runs on the upper surface of the rod or guide rail 22. The head 32 is forked or bifurcated to receive the roller 33 and the 105 rod 22, so that accidental disconnection of the rod 22 from the head 32 is prevented. The link 31 extends through an opening in a bracket 34 on the machine frame, whereby it is supported and guided. The threaded 110

connection of the head 32 to the link 31 permits the effective length of the link to be adjusted. The shaft 29 with its connected rock arms forms a rock-frame operable by each shift key separately to transmit motion to the platen-shifting frame.

A stop-nut 35 on the threaded portion of the link 31 by striking the bracket 34 limits the downward movement of the link 31 and thereby determines the upper case position of the platen; the nut 35 being adjustable on the rod and locked in position by a lock nut 35'. A washer 36 of leather or other suitable material may be interposed between the nut 35 and the bracket if desired, to act as a buffer and sound-deadener. The cam surfaces 27 may be formed to obtain any desired movement of the platen relative to the movement of the shift keys. Springs 37 on the carriage bear upwardly on the tie-rod 11 to partially counterbalance the weight of the platen, and the shift keys are returned by springs 38.

When a shift key is depressed, the shaft 29 is rocked and pulls the link 31 downwardly, thereby rocking the frame comprising the rod 22 and arms 19 about the pivots 20 and swinging the platen frame about the axis of the rod 10; the platen being thus carried from lower case position (Fig. 2) to upper case position (Fig. 3). The rod 22 on which the roller 33 runs being parallel with the direction of the carriage travel, the shifting movements of the platen are the same regardless of the position of the carriage.

Variations may be resorted to within the scope of the invention, and portions of the improvements may be used without others.

Having thus described my invention, I claim:

1. In a typewriting machine, the combination, with a carriage, of a tilttable platen frame pivoted on said carriage and comprising end plates and rods connecting the same, one of said rods disposed in rear of the other rod and constituting the axis about which said frame tilts; a shifting member pivoted intermediate its ends on said carriage and extending forwardly beneath and into direct engagement with said other rod; and means for depressing the rear portion of said shifting member and thereby elevating its forward portion, so as to tilt said platen frame upwardly into upper case position.

2. In a typewriting machine, the combination, with a carriage; of a tilttable platen frame pivoted on said carriage and comprising end plates and rods connecting the same, one of said rods disposed in rear of the other rod and constituting the axis about which said frame tilts; a shifting member pivoted intermediate its ends on said carriage and having an arm which extends forwardly beneath said other rod and upon

which the latter rests, so as to support said frame, and also having a rearwardly-extending arm; and means connected to exert a downward pull upon the second-named arm, so as to depress the same and thereby elevate the first-named arm, to tilt said platen frame upwardly into upper case position.

3. In a typewriting machine, the combination of a carriage, a platen shifttable thereon, a platen-shifting frame tiltably mounted on the carriage and comprising a horizontal rail, a vertically shifttable rod, a roller carried thereby and running on said rail, a bracket on the machine frame in which said rod is guided, and a stop on said rod in position to engage said bracket and thereby limit the movement of the rod.

4. In a typewriting machine, the combination of a carriage, a platen shifttable thereon, a platen-shifting frame tiltably mounted on the carriage and comprising a horizontal rail, a vertically shifttable rod, a roller carried thereby and running on said rail, bracket on the machine frame in which said rod is guided, a stop adjustable on said rod, and a coöperating counter-stop on the machine frame.

5. In a typewriting machine, the combination of a carriage, a platen shifttable thereon, a platen-shifting frame tiltably mounted on the carriage and comprising a horizontal rail, a vertically shifttable rod, a roller carried thereby and running on said rail, a bracket on the machine frame in which said rod is guided, a stop adjustable on said rod, a coöperating counter-stop on the machine frame, and a buffer interposed between said stop and counter-stop.

6. In a typewriting machine, the combination with a carriage and a platen frame pivoted thereon, of a platen rotatable on said frame, the carriage formed with curved guides concentric with the pivot of the platen frame and in which the platen axle is supported and guided, a platen shifting frame mounted to swing on the carriage and arranged to lift the platen frame, a shift key, and means operated thereby having a running connection with said shifting frame behind the carriage for operating said shifting frame to shift the platen.

7. In a typewriting machine, the combination with a machine frame and a carriage mounted for travel thereon, of a platen frame pivoted on the carriage, a platen having an axle journaled in the platen frame forward of the platen frame pivot, the carriage being provided with curved guiding slots concentric with the platen frame pivot, and in which the platen axle is guided, said slots forming a support for the platen when in lower case position, a platen shifting frame pivotally mounted on the carriage and extending forwardly from its pivot to engage beneath the platen frame and shift the

latter when the shifting frame is rocked, said shifting frame comprising a rod at the rear of the carriage and extending in the direction of the carriage travel, independently operable shift keys, and means operated thereby having a running connection with said rod for shifting the platen.

8. In a typewriting machine, the combination with a carriage and a platen shiftable thereon, of a platen shifting frame tiltably mounted on the carriage, and an actuating device for said frame mounted on the machine frame and having a running connection with the tilting frame for actuating the latter while the carriage is at any point in its travel, said actuating device and machine frame having co-operating stops to limit the movement of the actuating device and thereby determine the shifted position of the platen, one of said stops being adjustable to vary the stop position of said actuating device to thereby adjustably vary said shifted position of the platen.

9. In a typewriting machine, the combination of a carriage; a platen shiftable thereon; a platen-shifting frame tiltably mounted on the carriage and comprising a horizontal rail; a vertically shiftable rod; a roller carried thereby and running on said rail; a rock shaft journaled in the machine frame; a pair of rock arms secured to said shaft, one of said arms extending forwardly and the other rearwardly, the last-named arm having the lower end of said rod connected thereto; and a shift key pivoted intermediate its ends in said machine frame and having its rear end operatively engaged with the forwardly-extending rock arm.

10. In a typewriting machine, the combination of a carriage; a platen shiftable thereon; a platen-shifting frame tiltably mounted on the carriage and comprising a horizontal rail; a vertically shiftable rod; a roller carried thereby and running on said rail; a rock shaft journaled in the machine frame; a forwardly-extending rock arm secured to said shaft and having its front end provided with a cam surface; a shift key pivoted intermediate its ends in said machine frame and having its rear end provided with a roller to engage said cam surface, so as to rock said shaft when said key is depressed; and a connection between said shaft and said rod for lowering the latter when said shaft is rocked.

11. In a typewriting machine, the combination of a carriage; a platen shiftable thereon; a platen-shifting frame tiltably mounted on the carriage and comprising a horizontal rail; a vertically shiftable rod; a roller carried thereby and running on said rail; a rock shaft journaled in the machine frame; a pair of rock arms secured to said shaft, one of said arms extending forwardly and the other rearwardly; the rearwardly-

extending arm having the lower end of said rod connected thereto, and the forwardly-extending arm being provided with a cam surface; and a shift key pivoted intermediate its ends in said machine frame and having its rear end provided with a roller to engage said cam surface, so as to rock said shaft when said key is depressed.

12. In a typewriting machine, the combination of a carriage; a platen shiftable thereon; a platen-shifting frame tiltably mounted on the carriage; a rock shaft journaled in the machine frame; a pair of forwardly-extending rock arms fixed to said shaft adjacent its opposite ends, each arm having its front end provided with a cam surface; a pair of independently-operable shift keys pivoted intermediate their ends in said machine frame, each key having a roller at its rear end over which the cam surface on the adjacent rock arm projects, so as to rock said shaft when either key is depressed; and a connection between said shaft and said shifting frame, including a rock arm fixed to said shaft intermediate the first-named rock arms, for tilting said frame when said shaft is rocked.

13. In a typewriting machine, the combination of a carriage; a platen shiftable thereon; a platen-shifting frame tiltably mounted on the carriage; a rock shaft journaled in the machine frame; a pair of forwardly-extending rock arms fixed to said shaft adjacent its opposite ends, each arm having its front end provided with a cam surface; a pair of independently-operable shift keys pivoted intermediate their ends in said machine frame, each key having a roller at its rear end over which the cam surface on the adjacent rock arm projects, so as to rock said shaft when either key is depressed; a rearwardly-extending rock arm fixed to said shaft between said forwardly-extending arms; and a vertical connection between said rearwardly-extending arm and the rear portion of said frame for tilting said frame when said shaft is rocked.

14. In a typewriting machine, the combination of a carriage; a platen shiftable thereon; a platen-shifting frame tiltably mounted on the carriage; a vertically-shiftable rod having a running connection with said frame for shifting the latter and the platen into upper-case position when said rod is lowered; a rock shaft journaled in the machine frame and having a rearwardly-extending rock arm fixed to it, said rod connected at its lower end to said arm; a shift key connected to rock said shaft and thereby lower said rod; and co-operating stops on said rod and the machine frame for limiting the downward movement of the rod, and thereby determining the upper-case position of the platen.

15. In a typewriting machine, the combi-

1. In a typewriting machine, the combination of a carriage; a platen shiftable thereon; a platen-shifting frame tiltably mounted on the carriage; a vertically-shiftable rod having a running connection with said frame for shifting the latter and the platen into upper-case position when said rod is lowered; a rock shaft journaled in the machine frame and having a rearwardly-extending rock arm fixed to it, said rod connected at its lower end to said arm; a shift key connected to rock said shaft and thereby lower said rod; a guide bracket in which said rod is slidably engaged secured to the machine frame; and a stop on said rod engageable with said bracket for limiting the downward movement of the rod, and thereby determining the upper-case position of the platen.
2. In a typewriting machine, the combination, with a carriage; of a platen frame pivoted on said carriage; a platen having its axle journaled in said frame forward of the pivot thereof, said carriage being provided with curved guide slots concentric with said pivot and forming a support for the platen when in lower-case position; a rocking platen-shifting frame mounted on said carriage and extending forwardly beneath the platen frame into position to engage and lift said platen frame and platen into upper-case position when said shifting frame is rocked; a shift key; and connections between said key and said shifting frame for rocking the latter when the former is depressed.
3. In a typewriting machine, the combination, with a carriage, a platen frame pivoted on said carriage, and a platen mounted in said frame; of a platen-shifting frame pivoted on said carriage at an intermediate point thereof and comprising curved end members on the forward portions of which said platen frame rests; and means connected with said shifting frame in rear of its pivot for depressing the rear end thereof and raising the front end, so as to cam said platen frame and platen upwardly into upper-case position.
4. In a typewriting machine, the combination, with a carriage, a platen frame pivoted on said carriage, and a platen mounted in said frame; of a rocking platen-shifting frame comprising curved end members pivoted at an intermediate point thereof to said carriage, and a rod connecting the rear portions of said members, said platen frame resting, in advance of its pivot, upon the forward portions of said members; and means acting upon said rod for depressing the first-named portions of said members 60 and thereby elevating the second-named portions thereof, so as to cam said platen frame and platen upwardly into upper-case position.
5. In a typewriting machine, the combination, with a carriage; of a tilttable platen frame pivoted on said carriage and comprising end plates and rods connecting the same, one of said rods disposed in rear of the other rod and constituting the axis about which said frame tilts; a shifting cam pivoted intermediate its ends in said carriage and having its front portion extending beneath the forward frame rod for engagement therewith; and means for depressing the rear end of said cam and thereby elevating its front end, so as to cam said platen frame upwardly into upper-case position.
6. In a typewriting machine, the combination, with a carriage; of a tilttable platen frame pivoted on said carriage and comprising end plates and rods connecting the same, one of said rods disposed in rear of the other rod and constituting the axis about which said frame tilts; a rocking platen-shifting frame pivoted in said carriage at an intermediate point thereof and comprising curved end members whose forward portions extend beneath the forward platen frame rod for engagement therewith; and means connected with said shifting frame in rear of its pivot for depressing the rear end thereof and raising the front end, so as to cam said platen frame upwardly into upper-case position.
7. In a typewriting machine, the combination, with a carriage; of a tilttable platen frame pivoted on said carriage and comprising end plates and rods connecting the same, one of said rods disposed in rear of the other rod and constituting the axis about which said frame tilts; a rocking platen-shifting frame comprising curved end members pivoted at an intermediate point thereof to said carriage, and a rod connecting the rear portions of said members, the forward portions of said end members extending beneath the forward platen frame rod; and means connected with said shifting frame rod for depressing the first-named portions of said end members and thereby elevating the second-named portions thereof, so as to cam said platen frame upwardly into upper-case position.
